CLAIM

The ornamental design for a globe and stand, as shown and described.

DESCRIPTION

FIG. 1 is a right side elevational view of the globe and stand of my design;

FIG. 2 is a left side elevational view thereof;

FIG. 3 is a front elevational view thereof;

FIG. 4 is a rear elevational view thereof;

FIG. 5 is a top view thereof;

FIG. 6 is a bottom plan view thereof; and,

FIG. 7 is a perspective view thereof.

The broken lines shown the interior of the circular area of the stand portion of the globe and stand shown in FIG. 6 is included for the purpose of illustrating a portion of the globe and stand that forms no part of the claimed design.
